STILT

John Kopp, Lunenburg, Mass.

Application May 29, 1957, Serial No. 46,392

Term of patent 14 years

(Cl. D34—5)

Fig. 1 is a perspective view of a stilt embodying my design;

Fig. 2 is a side elevation looking from the right at the stilt of Fig. 1; and

Fig. 3 is a bottom plan of the stilt step of Fig. 1.

I claim:

The ornamental design for a stilt, substantially as shown.
